UNITED STATES PATENT OFFICE.

JOHN C. HOEHNEN, OF BUSHNELL, ILLINOIS.

TROUGH.

Application filed November 12, 1923. Serial No. 674,177.

To all whom it may concern:

Be it known that I, JOHN C. HOEHNEN, a citizen of the United States, and a resident of the city of Bushnell, in the county 5 of McDonough and State of Illinois, have invented certain new and useful Improvements in a Trough; and I do hereby declare that the following is a full, clear, and exact description of the same, reference being had 10 to the accompanying drawings, and to the numerals of reference marked thereon, which form a part of this specification.

This invention relates to a trough especially adapted for feeding hogs, but susceptible of other and various uses and comprises a one piece sheet metal member which is stamped and formed into proper shape to provide maximum strength and 15 rigidity.

20 The invention consists in the novel structural features hereinafter described and more particularly pointed out and defined in the appended claims.

25 In the accompanying drawings which illustrate a preferred embodiment of this invention, and in which similar reference numerals refer to similar features in the different views,

Figure 1 is a side elevational view of the 30 trough with parts in section.

Figure 2 is a top plan view of the trough.

Figure 3 is a top plan view of the sheet metal blank from which the trough is made.

In referring to the drawing, it will be 35 observed that a one-piece sheet metal blank has been illustrated for forming the trough. In the present embodiment of this invention, the blank is substantially oblong having its corners cut off excepting for the 40 marginal end portion which forms the supporting feet 1.

At suitable distances from the ends of the blank depending upon the desired height of the trough, substantially square pieces have 45 been cut from opposite sides of the blank. These cut out portions are designated by the reference numeral 2. A transversely extending incision 3 extends from the inner end of each cut portion to a suitable depth 50 across the blank and outwardly extending incisions 4 occur at the outer walls of the slots. The incisions 4 form flaps 5 which are bent to form attaching flanges or flaps for the ends of the trough as will later 55 appear.

In forming the trough from the afore-

described blank, the margins 1 are bent at right angles to the end supports or legs 6 defined by the dotted lines 7 and 8. Likewise, the flaps 5 are bent at right angles to the triangular lateral margins or wings 9 defined by the dotted lines 10. The triangular margins 9 are adapted to be bent later at right angles to the legs 6 where the parts are assembled. The lateral margins 65 11 of the body portions are then crimped to provide a half bend resulting in an upper horizontal flange to strengthen the structure. It will, of course, be understood that the different parts are bent or crimped 70 downwardly with reference to Figure 3. The body 12 of the trough is next stamped into a substantially concave shape as shown in Figures 1 and 2. During such operation, the portions 13 defined by the dotted lines 75 14 will form the ends of the trough, and the triangular portions 15 defined by the dotted lines 14 and 16 will be drawn or pinched together as shown in Figure 1. As the ends 13 of the trough are stamped inwardly, the 80 top end portions 17 defined by the dotted lines 18 and 8 will be brought inwardly over the top of the body portion 12 as shown in Figures 1 and 2 and are secured in superposed relation by means of bolts or 85 the like. The end supports or legs 6 may then be bent down at right angles and the triangular portions 9 folded or bent inwardly at right angles bringing the flaps 5 directly under the half beads 11 and securing the same by the same bolt that secured the top end portions 17. Thus the 90 holes 19, 20 and 21 will be brought into registry for receiving a common bolt. Of course, it will be understood that the parts 95 may be secured by welding, soldering or any well known means. If desirable, the body of the formed trough may be transversely braced by a strip 22 connected to the top of the half beads.

100 It will, of course, be understood that while I have described a certain method of forming the trough, the necessary series of steps may be varied according to the desires of the workman. Thus the body may first be formed; then the ends may be properly fashioned as desired and secured to the body.

105 From the foregoing, it will be apparent that a strong and durable trough has been 110 provided from a one-piece sheet metal blank that can be easily and quickly manufactured

at minimum expense and that may be anchored or attached by its supporting feet.

I am aware that many changes may be made, and numerous details of construction 5 may be varied through a wide range without departing from the principles of this invention and I therefore do not purpose limiting the patent granted otherwise than necessitated by the prior art.

10 I claim as my invention:

1. A trough comprising a one-piece metal member having a concave body portion provided with horizontal marginal flanges, end top portions in superposed relation with 15 said flanges, end supports integral with said top portions, and lateral wings on said end supports having upper flanges attached beneath said marginal flanges.

2. A trough comprising a one-piece metal 20 member having a concave body portion pro-

vided with marginal flanges, ends terminating in top portions superposed upon said flanges, and end supports integral with and extending downwardly from said superposed portions.

3. A trough, comprising a one-piece metal member having a concaved body portion provided with marginal flanges, ends terminating in top portions superposed upon said flanges, end supports integral with and extending downwardly from said superposed portions, lateral wings on said end supports underlying said marginal flanges and end top portions, and a single connecting means at each corner of the trough 30 uniting said marginal flanges, top portions and wings.

In testimony whereof I have hereunto subscribed my name.

J. C. HOEHNEN.
